UNITED STATES PATENT OFFICE

SIDNEY T. FARRELL, OF NEWTONVILLE, MASSACHUSETTS

GAME

Application filed May 1, 1929. Serial No. 359,645.

This invention relates to indoor games and more especially to those based on racing and involving an element of chance.

Most, if not all, of the racing games of this type are open to the objection that the first racer to start has a substantial advantage and with an even break in luck will usually finish first. The players necessarily take turns, and consequently the last player to start has only 10 a small chance of winning.

The present invention deals particularly with this condition, and it aims to devise a racing game in which all of the players will have approximately an even chance. In the 15 preferred embodiment of the invention this is accomplished by running the race on a time basis, each move on the game board or chart representing a given unit of elapsed time.

The invention may be embodied in a great 20 variety of racing games, but for purposes of disclosure the invention will be herein described as embodied in a game based on a hundred yard dash.

The nature of the invention will be readily 25 understood from the following description when read in connection with the accompanying drawings, and the novel features will be particularly pointed out in the appended claims.

30 In the drawings,

Figure 1 is a plan view of a chart embodying features of this invention;

Fig. 2 is a plan view of a chart of entrance fees;

35 Fig. 3 is a plan view of a score card;

Fig. 4 is a perspective view of dice which may be used in playing the game; and

40 Figs. 5 and 6 are plan views of markers and chips, respectively, which may also be used in the game.

Referring first to Fig. 1, the chart there shown represents a race course divided longitudinally into four lanes indicated at A, B, C and D, respectively. The course also is 45 divided by transverse lines into spaces, which in this case represent yards of distance. Numbers are associated with the lines to indicate the distance from the start so that the progress of the racer can be measured and indicated. Those figures on the opposite mar-

gins 2 and 3 of the chart designate the ten yard intervals, and these figures preferably face in opposite directions, while additional figures located in aisles 4, 5 and 6 between the lanes designate the intermediate yard intervals. Preferably the figures in the aisle 4 point toward the left, those in the aisle 6 toward the right, and those in the middle aisle 5 toward the bottom of the chart in order to facilitate the reading of the figures by the 60 different players.

In a hundred yard dash the drive for the finish occurs in the last ten or twelve yards and corresponds to what may be termed the "home stretch" or the "last lap" in some other races. For convenience this part of the course will be hereinafter referred to generically as the "home stretch" in order to distinguish it from the main part of the course. In the chart shown the home stretch is divided into twelve equal spaces and a time 65 designation is associated with each division line or each space, the figure in each space indicating in hundredths of a second the time assigned to the runner to reach the finish line from the line at the bottom of the respective space in which the figure appears. Roughly the time required to cover this twelve yards of home stretch is approximately one second,

and the times assigned in the different lanes 70 varies somewhat, as will be obvious from an inspection of the chart. For example, it will be observed that the time designations in the home stretch of lane A are smaller than those for corresponding distances in any of the other lanes. Those in lane D are longer than in any other lane, and those in lanes B and C are intermediate in value. This variation in the time designations in the different lanes 75 obviously make some lanes more favorable

for the runners than others. Certain penalties or set backs also are included in some or all of the lanes. For example, the circles 80 in the lanes A and C designate a break in stride for which two yards are deducted from the runners distance, while the diamonds 8 in lanes B and D indicate that the runner 85 has "beat the gun", and will be penalized one yard on the new start.

The movements made by the racers may be 90 95 100

determined or originate in various ways, as for example, by dealing or selecting a card, turning a spinner, throwing dice, or by any other device involving a suitable element of chance. In the particular arrangement shown two dice X and Y are provided, the die X bearing the numbers 9, 10 and 11, while the die Y bears the numbers 8, 9, 10 and 11, these numbers designating yards of distance. Preferably these dice are of different colors, the die X being red, for example, and the die Y white. One or the other is used, depending upon the supposed rating of the contestants, the red die being slightly more favorable to the runner than the white die.

In view of the fact that certain of the lanes are more favorable to the runner than others, the chances of the players, in the long run, are made more equal by an arrangement of entrance fees which places a higher price on the more favorable lanes. The chart 10 shown in Fig. 2 illustrates a suitable arrangement of entrance fees.

It is determined prior to starting the game whether to play with the red or the white die, the deciding factor being simply the preference of the players and being based on the ability or ratings of the runners who are supposed to compete. Assuming that the red die is to be used, the player backing the runner in lane A pays eight chips, that in lane B four chips, etc. The chips may simply consist of disks such as that indicated at 12 in Fig. 6, or poker chips may be used.

In playing the game the runners and the lanes in which they are respectively to run may be selected by agreement or by rolling both dice, the higher throw having first choice. The individual runners are represented by markers or checkers, such as that indicated at 14 in Fig. 5, and they may, if desired, be named for well known sprinters, such as Paddock, Borah, and others. The players then roll the dice in turn, the player who backs the runner in lane A starting first. Assuming that he uses the red die and the figure 11 comes uppermost, he moves the marker 14 on to the eleven yard line. The other player or players roll the dice in turn and move their respective markers on to the line corresponding to the respective figures which they turn up. Each roll of the dice represents one second of elapsed time. Assuming, for example, that Paddock is running in lane A and Borah in lane B, Williams in lane C and Wyckoff in lane D, and the checker or marker 14 for either Borah or Wyckoff should land on line 11 which, as indicated by the foot note is a penalty line in these two lanes, the race would start over and the penalized runner would be set back one yard for jumping the gun.

The players continue to roll the dice in turn and to advance their respective runners in ac-

cordance with the respective numbers turned up at each roll, until at the completion of the eighth turn for each player, indicating eight seconds of elapsed, time Paddock might be found in lane A on line 84, Borah in lane B on line 82, Williams in lane C on line 83, and Wyckoff in lane D on line 79. The die is again rolled for Paddock in lane A, and assuming that he gets 11 for his ninth turn or ninth second of elapsed time, this would place him on line 95. If Borah gets 10 for his ninth turn he is placed on line 92. Williams getting a 9 places him on line 92, while Wyckoff getting, say, an 8, places him on line 87, which would not bring him into the home stretch. He requires another turn, therefore, and if we assume that he gets 11 on this turn he would then be on line 98 in ten turns or ten seconds. The time required for Paddock to finish from line 95 is shown on the chart to be six-tenths of a second; that required for Borah to finish from line 92 would be seventy-six hundredths of a second; that necessary for Williams to finish from line 92 is seventy-five hundredths of a second; while that given to Wyckoff to finish from line 98 is thirty-two hundredths of a second. Consequently, the time made by each of the runners is, Paddock 9.6 seconds, Borah 9.76 seconds, Williams 9.75 seconds, and Wyckoff 10.32 seconds. The player backing Paddock, therefore, would be the winner and take all the chips or entrance fees put up for this particular race.

In order to facilitate keeping the score, score cards like that shown at 15 in Fig. 3 may be used, a check mark being placed under each numbered turn as the dice is rolled for each individual player. In other respects the use of the score card will be obvious simply from an inspection of it.

Any number of runners may be entered in any race, but if more than four are entered, trial heats will be necessary. For example, with eight runners entered, two trial heats are run and the first and second place winners of each heat qualify for the final heat. The winner of each trial heat takes the chips of the men eliminated. The entrance fee of the runner taking second place in each trial heat is returned to him. In the final heat the winner takes all the chips.

By properly charting the race course and suitably selecting the distances and the fractions of time in the home stretch, essentially the same arrangement may be applied to a great variety of racing games where time is a factor, such for example, as boat races, horse, automobile, airplane races, and the like.

The charts shown in Figs. 1 and 2 may be printed on paper and applied to a suitable board or backer, or they may be supported in any convenient manner.

a typical embodiment of my invention, it will be understood that this disclosure has been made rather by way of illustration than limitation, and that the invention may be embodied in a considerable variety of forms without departing from the spirit or scope thereof.

Having thus described my invention, what I desire to claim as new is:

10 1. In a game, a chart having a race course marked thereon, said race course including divisions for indicating the progress of the racers and also having a home stretch divided and bearing indicia to indicate the 15 time required by a racer to finish from certain specified points in the home stretch.

2. In a game, a chart having a race course marked thereon, said race course including divisions for indicating the progress of the 20 racers and also having a home stretch divided and bearing indicia to indicate the time required by a racer to finish from certain specified points in the home stretch, and a device for determining by chance the 25 distance covered by a racer in a given interval of time.

3. In a game, a chart having a race course marked thereon, said course including a main section and a home stretch section, both of 30 said sections being divided into spaces, and time designations associated with the divisions in said home stretch.

4. In a game, a chart having a race course marked thereon, said course including a main 35 section divided into approximately equal spaces, and a home stretch section divided into substantially equal spaces, distance designations associated with the spaces in said main section, and time designations associated with the divisions in the home stretch section and serving to indicate the time required by a racer to finish from certain specified points in the home stretch.

5. In a game, a chart having a race course 45 marked thereon, said course being divided into lanes each including a main section and a home stretch section, both of said sections being divided into spaces, and designations associated with the divisions in the home 50 stretch section and indicating the time required by a racer to finish from certain specified points in the home stretch.

6. In a game, a chart having a race course marked thereon, said course being divided 55 into lanes each having divisions for indicating the progress of the racers and a home stretch divided into spaces, and designations associated with said spaces to indicate the time required by a racer to finish from certain 60 specified points in the home stretch, the time designations varying in the different lanes.

7. In a game, a chart having a race course marked thereon, said course being divided 65 into lanes, each of said lanes including a main

section and a home stretch section, penalties in certain of said lanes, both of said sections of each lane being divided transversely into spaces, and designations associated with the divisions in the home stretch sections for indicating the time given the racer to finish from certain specified points in the home stretch, the time designations varying in different lanes.
